(57) **CLAIM**

The ornamental design for a planter, as is shown and described.

DESCRIPTION

FIG. 1 is a perspective view of a planter showing our new design;

FIG. 2 is a top plan view thereof, with drainage holes shown in broken line and forming no part of the claimed design;

FIG. 3 is a front elevation view thereof;

FIG. 4 is a partial front elevation view thereof, showing only region 4 of FIG. 3 at an enlarged scale;

FIG. 5 is a bottom plan view thereof, with drainage holes shown in broken line and forming no part of the claimed design;

FIG. 6 is a back elevation view thereof; and,

FIG. 7 is a right side elevation view thereof, with the left side elevation view being a mirror image thereof.
